UNITED STATES PATENT OFFICE.

CHARLES NELSON, OF NEW YORK, N. Y., ASSIGNOR TO S. STERNAU & CO., OF BROOKLYN,
NEW YORK, A COPARTNERSHIP.

DESIGN FOR A GRATE FOR VAPOR-STOVES.

No. 39,925.

Specification for Design.

Patented April 20, 1909.

Application filed February 9, 1909. Serial No. 477,035. Term of patent 14 years.

To all whom it may concern:

Be it known that I, CHARLES NELSON, a subject of the King of Sweden, residing in the borough of Brooklyn, county of Kings, city and State of New York, have invented a new, original, and ornamental Design for a Grate for Vapor-Stoves, of which the following is a specification, reference being had to the accompanying drawing, forming a part thereof and showing a perspective view of the design.

The design comprises a grate, having a

ring-like outside member from which converge a plurality of Y shaped bars with curved bifurcated ends, the bars being joined to the ring at their bifurcated ends.

I claim:

The ornamental design for grate for vapor stoves as shown and described.
